ABSTRACT

Coal is solvent extracted with a solvent containing a mixture of hydroaromatic hydrocarbons and saturated aliphatic hydrocarbons to produce a liquid coal extract which has a low asphaltenes content and is distillable without prior hydrogen treatment of the extract liquids.

2 Claims, No Drawings

COAL LIQUEFACTION PROCESS

BACKGROUND OF INVENTION

This invention concerns a process for converting solid carbonaceous materials such as coal into liquid hydrocarbonaceous products. More particularly, this invention relates to a process for solvent extracting coal to provide hydrocarbonaceous liquid suitable for use as substitutes for petroleum liquids.

Solvent extraction of coal and similar solid carbonaceous materials is known as a method for producing hydrocarbonaceous liquids. The liquid product from these extraction operations may be substituted for petroleum fractions and can be refined to produce gasoline, etc., in a manner analogous to that used to refine petroleum. Because of the abundance of coal reserves and decreasing petroleum resources, it is becoming increasingly important to develop practical methods for deriving petroleum substitutes from coal.

In a typical operation for solvent extraction of coal, the coal is pulverized and mixed with a hydrocarbonaceous solvent. The mixture of coal and solvent, generally with added hydrogen gas, is subjected to heat and pressure. A fraction of the coal is dissolved and mixes with the solvent. The liquid mixture of solvent and dissolved coal is then separated from the coal ash and undissolved coal by settling, filtration, etc.

Two problems in particular have caused substantial difficulties in developing an economical operation for solvent extracting coal. These can be characterized briefly as, first, inability to facilitate the transfer of sufficient hydrogen into the hydrogen-deficient coal during the extraction step, and second, lack of selectivity of the solvent in extracting particular components of the coal.

Since the coal to be extracted is relatively low in hydrogen content, it is necessary to add a significant amount of hydrogen to the coal during the solvent extraction operation. In order to form coal liquids which can be used as substitutes for petroleum fractions, the hydrogen content of the coal to be liquefied must be increased typically from about 5 wt.% up to about 10 wt.% or more. Prior art has devised several methods for facilitating the necessary hydrogen addition. Of these, the most commonly suggested have been the use of extraneous catalysts and the use of hydrogen donor solvents. The use of extraneous catalysts has been found generally impractical. These catalysts rapidly become poisoned by the metals present in the coal, and are quite difficult to separate from the solid residue remaining after the extraction operation. Hydrogen donor solvents have provided a partial solution to the problem of transferring hydrogen into the coal. These solvents donate hydrogen to the coal molecule and simultaneously revert from a partially saturated to an aromatic structure. However, the amount of hydrogen which hydrogen donor solvents can typically transfer into the coal is quite limited, and a further hydrogenation treatment subsequent to the extraction operation is generally necessary when using them to extract the coal.

Lack of selectivity of coal solvents in extracting the various available components of coal is partly related to the inability of solvents to transfer sufficient hydrogen into the coal, as discussed above. Lack of selectivity is found generally in prior art solvents, but will be

discussed hereinafter in terms of hydrogen donor solvents, since they have generally been employed to the exclusion of other solvents. Hydrogen donor solvents are capable of dissolving a large fraction of the solid coal, often as much as 70-80%. Unfortunately, the coal liquid obtained by using hydrogen donor solvents invariably contain as much as 40-50% of undesirable components which are substantially refractory to further refining, are severely hydrogen-deficient, and which severely inhibit separation and refining of the more valuable components of the coal extract. For convenience, these undesirable components of the coal extract can be characterized as benzene-insoluble components and benzene-soluble but heptane-insoluble components. The benzene-insoluble fraction of coal liquids is generally thought to result from polymerization of components of the coal after they are dissolved in the solvent. During the extraction operation, the coal molecules are depolymerized and partially hydrogenated. Because of the lack of available hydrogen, a significant fraction of the liquefied material remains in an easily polymerizable state and tends to repolymerize rapidly to form undesirable, high molecular weight compounds which are even more refractory than the original solid coal. Since prior art solvents, including the hydrogen donor type, are unable to supply enough hydrogen to saturate or crack these polymerizable compounds, they rapidly convert to undesirable, benzene-insoluble, refractory compounds in prior art operations. It is apparent that simply dissolving a very large fraction of the solid coal without adequate hydrogenation is not only futile, but actually undesirable. The polymerizable compounds which are thereby produced cannot be adequately hydrogenated using prior art solvents and will rapidly form undesirable and untreatable benzene-insoluble compounds. It has been found that a supply of hydrogen gas mixed with prior art solvents and coal during the extraction operation is not sufficient to provide an adequate source of hydrogen which can be effectively utilized in the extraction operation, since uptake of the hydrogen gas into the solvent and transfer therefrom into the coal molecules is not rapid enough.

The benzene-soluble but heptane-insoluble fraction in coal liquids is herein termed the "asphaltene" fraction. Generally, a hydrogen donor solvent dissolves a significantly large amount of asphaltenes, e.g., about 10% or more of the dissolved coal. Asphaltenes are high molecular weight, hydrogen-deficient compounds which are quite refractory to conventional refining techniques. A particular drawback of asphaltenes is that they are undistillable and heat sensitive, and tend to form coke when exposed to distillation temperatures. This property of asphaltene makes it quite difficult to distill the coal liquids recovered in prior art operations. Asphaltenes are difficult to treat and to separate from more valuable components of the coal extract. They are, therefore, a highly undesirable fraction, and any reduction in the amount of asphaltenes contained in the coal liquid extracted is quite desirable.

Because of the refractory and/or heat sensitive nature of a substantial fraction of coal extracts produced in prior art operations, and because of the presence of readily polymerizable compounds in coal liquid after the extraction step, it has been found impractical to attempt to perform conventional refining operations,

e.g., catalytic cracking and distillation, on the coal liquids as they are recovered from the extraction operation. A further hydrogen treatment of the coal liquid after solvent extraction has been found necessary in order to make the coal liquids suitable for catalytic cracking, etc. This type of hydrogenation is cumbersome and entails the use of expensive catalysts and high temperatures. The expense and difficulty of such post-extraction hydrogenation operations has been a significant barrier to the development of a successful process for solvent extracting coal to provide petroleum substitutes. As described above, the use of extraneous catalysts during the solvent extraction step itself, although successful in producing distillable coal extracts, is technically difficult and also prohibitively expensive, partly because of the necessity for very large scale catalyst regeneration facilities. Such catalysts deactivate rapidly and are difficult to separate from solid residues.

A drawback generally found in prior art liquefaction solvents and processes is the effect of the extraction operation on coal subjected to extraction conditions which is not dissolved during the operation. Any coal which is not dissolved in a first extraction operation has been found quite refractory to any further extraction. This is partly the result of the failure, discussed above, of prior art solvents to transfer sufficient quantities of hydrogen into the coal during the extraction step. The coal not dissolved is quite hydrogen-deficient, and has, if anything, less hydrogen content than the original coal. Coal is thus degraded into a relatively undesirable form by prior art extraction methods, and is not further extractable in a practical manner. Since the object of a solvent extraction operation is to convert coal into petroleum substitutes, it is obviously desirable to treat the coal in a manner which converts any unliquefied, solid coal to a form susceptible to conversion to a liquid rather than degrade the unliquefied coal into merely a low value fuel source. This degradation of the unconverted coal has been a barrier to successful solvent extraction operations when selective conversion of only a fraction of the coal has been attempted using, for example, hydrogen donor solvents.

SUMMARY OF INVENTION

An object of the present invention is to provide a process for the liquefaction of coal and similar carbonaceous solids to form distillable liquefaction products.

Another object of the present invention is to provide an extraction solvent capable of selectively extracting desirable components of a carbonaceous solid to provide hydrocarbonaceous liquids.

Another object of the present invention is to provide a process for solvent extraction of coal in which the liquefaction product is substantially free from non-distillable, coke-forming components.

Another object of the present invention is to provide a solvent for the extraction of coal which facilitates the transfer of hydrogen into the coal during the extraction operation.

Another object of the present invention is to provide a coal liquefaction process in which the coal liquids recovered are suitable for conventional catalytic cracking without prior hydrogenation treatment.

Another object of the present invention is to provide a process for solvent extraction of coal in which the liquid extraction product is substantially free from polymerizable, high molecular weight components.

Another object of the present invention is to provide a process for solvent extraction of coal which does not degrade unliquefied coal into an unextractable state.

In an embodiment, the present invention relates to a process for producing a liquid hydrocarbonaceous product from a solid carbonaceous material which comprises contacting the solid material, at solvent extraction conditions, with a solvent comprising a combination of a hydroaromatic hydrocarbon component and saturated aliphatic hydrocarbon components with a hydroaromatic component/saturated aliphatic components weight ratio of about 1:2 to about 2:1, and recovering the liquid hydrocarbonaceous product from the resulting mixture.

We have found that when a coal extraction solvent containing a mixture of hydroaromatic hydrocarbons and saturated aliphatic hydrocarbons at a volume ratio of about 1:2 to about 2:1 is employed to solvent extract coal, the coal liquids recovered are substantially free from polymerizable and coke forming components. Even more desirably, coal which is not liquefied during the extraction operation of the present invention and remains in solid form, is not degraded in any respect and may be efficiently utilized in further extraction operations. Among the apparent advantages of the present invention are the desirable properties of the liquid coal extracts derived from the extraction operation, which obviate the need for cumbersome and expensive post-extraction hydrogenation operations in order to render the extracts suitable for conventional catalytic cracking operations and provide a distillable liquefaction product directly from the liquefaction step. Other significant advantages derive from the lack of degradation of undissolved coal in the present extraction process, facilitating further extraction or other desired modifications of the coal not converted to a liquid in the extraction step.

DETAILED DESCRIPTION OF INVENTION

The solid carbonaceous materials which may be solvent extracted utilizing the process of the present invention include, in general, coal, lignite, peat, oil shale, tar sand, and like materials from naturally-occurring carbonaceous deposits. The present invention is particularly applicable to the conversion of bituminous coal. A typical preferred bituminous coal is an Illinois bituminous stoker coal having a volatiles content of about 5% or higher in the moisture and ash-free (MAF) coal. Although the following description is given with reference only to the preferred bituminous coal, the discussion is equally applicable to the other carbonaceous solid material noted above, unless otherwise stated. In general, better results are obtained in the present process when the coal to be extracted is pulverized to fairly small sized particles, e.g., 100 mesh particle size or smaller. However, pulverization to extremely small size is not essential to the present operation.

The solvent utilized in the present process to extract liquid products from coal contains a combination of particular relative amount of two distinct types of hydrocarbon compounds. The operative components of the present coal solvent are, first, hydroaromatic hydrocarbon components, and second, saturated aliphatic hydrocarbon components. It is essential to the present process that the solvent employed contain compounds from both of these two groups. Other hydrocarbons or extraneous materials may or may not be

present in varying amount up to about 20 wt.% of the total solvent without any particular adverse effect on the results obtained. Preferably, compounds not fitting into either of the two categories of essential components of the solvent are not present in the solvent at more than about 10 wt.% of the total solvent. The weight ratio of the two essential types of components in the solvent is an important aspect of effective operation in the present process, since the best results can be obtained only by maintaining the weight ratio within a specified range. Good results are obtained when the weight ratio of the hydroaromatic compounds to the saturated aliphatic compounds is maintained between about 1:2 and about 2:1. A preferred weight ratio range of hydroaromatics to aliphatic components is from about 2:3 to about 3:2. The hydroaromatic components of the solvent employed in the present process may be selected from a broad range of compounds which are characterized as partially hydrogenated condensed aromatic rings with from 1 to 4 (adjacent) CH_2 groups in which the carbon atom of the CH_2 group forms part of the condensed ring structure. An example of a hydroaromatic compound having non-adjacent CH_2 groups is 9,10-dihydroanthracene. An example of a hydroaromatic having two adjacent CH_2 groups is 9,10-dihydrophenanthrene. An example of a hydroaromatic having three adjacent CH_2 groups is indane. An example of a hydroaromatic having four adjacent CH_2 groups is tetrahydronaphthalene. The hydroaromatics suitable for use in the present process have boiling points above about 400°F. and preferably above about 500°F. It is generally preferred that the hydroaromatic fraction of the solvent of the present invention is a mixture of different partially hydrogenated polycyclic aromatic compounds, since pure hydroaromatic compounds, although giving equivalent results, are no more suitable than a mixture and are expensive to obtain. While the partially saturated naphthalenic hydrocarbons, i.e., dihydronaphthalene and tetrahydronaphthalene, are operative as hydroaromatic compounds in the present process, the preferred hydroaromatic hydrocarbons are higher boiling, partially saturated compounds with structures containing three or more condensed benzene nuclei. Examples of suitable compounds include partially hydrogenated anthracene and phenanthrene derivatives, etc. Other suitable compounds, by way of example, include the partially hydrogenated derivatives of naphthacene, benzanthracene, chrysene, benzophenanthrene, triphenolene, pyrene, pentacene, benzonaphthacene, pentaphene, benzochrysene, dibenzophenanthrene, dibenzoanthracene, picene, naphthantracene, benzopyrene, perylene, hexaphene, benzopentacene, hexacene, dibenzonaphthacene, dibenzochrysene, benzopentaphene, anthroanthracene, tribenzanthracene, naphthochrysene, benzopicene, phenanthrophenanthrene, naphthonaphthacene, benzopyrenes, dibenzopyrenes, heptacene, benzohexacenes, dibenzopentacenes, benzohexaphene, heptaphene, anthranaphthacene, naphthopenaphthene, benzonaphthochrysene, dibenzopicene, dibenzopentaphene, trinaphthalene, tetrabenzanthracene, benzonaphthonaphthacene, dibenzoperylene, naphthoperylene, dibenzopicene, naphthopicene, benzonaphthochrysene, coronene, etc. Particularly preferred hydroaromatic compounds include dihydrophenanthrene, dihydroanthracene, tetrahydroanthracene, dihydropyrene, tetrahydropyrene, and hexahy-

drocoronene. Partially saturated condensed ring compounds having one or more relatively short alkyl groups (e.g., 1-5 carbon atoms) in place of one or more of the hydrogen atoms in the condensed ring structure or similar phenyl group substituents are also suitable. It will be apparent to those skilled in the art that any mixture of partially hydrogenated polycyclic compounds which is derived from petroleum or coal liquids by, for example, partial hydrogenation of a particular fraction of the petroleum or coal oil, will generally contain at least a small fraction of most of the above listed compounds, their alkyl substituted or phenyl group substituted analogues, etc., in various states or partial saturation. As noted above, the compounds which are included in the term "hydroaromatic hydrocarbon" as used herein are those in which the condensed ring structure is at least partially aromatically unsaturated and at least partially saturated, with at least some of the saturated carbon atoms being bonded to hydrogen atoms. If this condition is satisfied, the presence or absence of short chain alkyl group substitutions, phenyl group substitutions, etc., is not of critical importance. These short alkyl chains and phenyl groups which replace the hydrogen atoms in the saturated portions of at least some of the condensed ring compounds are not believed to play any part in the solvent in the present process.

The saturated aliphatic components of the extraction solvent utilized in the present process include all types of alkanes and cycloalkanes having boiling points above about 400°F. and preferably above about 500°F. Thus, aliphatic saturates contained in a petroleum fraction which boils above about 400°F. (which can be characterized broadly as the kerosene fraction and heavier) may suitably be used to provide saturated aliphatic components for the present solvent. A mixture of saturates such as are typically found in commercial sources such as petroleum fractions, tar sand fractions, etc., is preferred over any particular saturated compound, because best results are obtained when a mixture of both paraffins and naphthenes is employed. Examples of suitable saturated aliphatic compounds which may be used, preferably in admixture, include C_{12} and heavier normal paraffins and isoparaffins, with at least C_{15} or higher molecular weight preferred, C_6 and longer-chain phenyl-substituted alkanes, alkyl naphthenes, fused ring naphthenic structures, etc. Specific examples of suitable saturated aliphatic structures include n-hexadecane and 1-ethyl-decahydronaphthalene.

A convenient and suitable solvent for use in the present process may be derived from the bottoms product remaining after vacuum distillation of crude petroleum. Critical to the use of any particular petroleum bottoms fraction is the requirement that the vacuum bottoms must contain condensed ring aromatic compounds and aliphatic compounds at an aromatic/aliphatic weight ratio of about 1:2 to about 2:1 and preferably about 2:3 to about 3:2. The vacuum bottoms are not, per se, employable as an adequate solvent, and must be treated to increase their hydrogen content to an adequate level before good results can be obtained in solvent extraction. Various suitable methods for hydrogen treating a vacuum bottoms fraction are known to those skilled in the art. By way of example, one method which is suitable for hydrogenation of such a petroleum or tar sand fraction and which is a preferred method for deriving the solvent used in the present process, includes pass-

ing a vacuum bottoms petroleum fraction over a fixed bed of a suitable catalyst at a temperature of about 700° to 800°F. and a hydrogen pressure of about 170 atmospheres or more. A suitable catalyst may, for example, be a combination of a Group VI metal and a Group VIII metal on a refractory inorganic support. One preferred catalyst for such an operation comprises a combination of nickel and molybdenum on an alumina-silica spherical support. Using such a catalyst, a suitable liquid hourly space velocity (total volume of charge per hour divided by the volume of catalyst) of about 0.5 to about 1 is generally maintained. Hydrogen is typically recycled in such an operation at a rate of about 5,000 to 15,000 cubic feet per barrel of hydrocarbon charged. After the vacuum bottoms have been processed in this or any other suitable manner in order to provide sufficient fractions of the hydroaromatic compound and saturated aliphatic compounds essential to the solvent of the present process, the light ends (material boiling below about 400°F. and preferably all materials boiling below about 500°F.) are removed by distillation. The bottoms product remaining after removal of these light ends is a preferred solvent in the present process. It is essential to the use of any petroleum fraction as a solvent in the present process that such a fraction contain both hydroaromatic compounds and saturated aliphatic compounds in particular relative amounts. Unless a particular hydrocarbon fraction contains both types of compounds in sufficient relative quantity, it is unsuitable. For example, slurry oils have been proposed as coal solvents but, unlike the suitable petroleum and tar sand vacuum bottoms, slurry oils are unsuitable for use in the present process even when subjected to hydrogen treatment as described above. This is believed to be the result of their composition, which is overly high in aromatics content and deficient in aliphatic compounds. Thus, unless a mixture of pure hydroaromatic compounds and saturated aliphatic compounds is specially prepared for use as a solvent, any particular hydrocarbon fraction sought to be employed as a solvent in the present process must be analyzed to determine its composition and, if either too high in aromatics content or aliphatic content, cannot be used. Those skilled in the art will recognize that the relative amount of aromatics and aliphatics in petroleum and tar sand fractions varies over a wide range depending on the source of the petroleum or tar sand, so that not all properly hydrogenated vacuum bottoms fractions are necessarily suitable. By analysis of particular petroleums, tar sands, and any other available sources of a heavy hydrocarbon fraction, and from the description herein, it will be apparent to those skilled in the art which hydrocarbon fraction may suitably be employed in the present process.

Solvent extraction conditions utilized in the present process include a temperature of about 600°F to about 850°F. and a pressure of about 100 atmospheres to about 350 atmospheres or more. A temperature of about 675°F. to about 800°F. and a pressure of about 150 atmospheres to about 250 atmospheres are preferred. The solvent and coal are admixed and charged to the extraction zone at a solvent/coal weight ratio of about 1:2 to about 10:1. A solvent/coal weight ratio of about 1:1 to about 3:1 is preferred. The process of the present invention may be embodied in either a batch type operation or a continuous type operation with

good results. In a batch type operation, a quantity of solvent and coal are admixed and placed in a suitable solvent extraction reactor, such as an autoclave, subjected to solvent extraction conditions therein, and then withdrawn after a suitable residence time. A residence time of about ½ hour to about 24 hours may be employed with good results in such embodiments, with a residence time of about 2 hours to about 6 hours being particularly preferred. In a continuous type operation, solvent and coal are continuously admixed, charged to a suitable solvent extraction reactor, maintained therein at extraction conditions for a suitable time, and continuously withdrawn. A suitable liquid hourly space velocity (volume of reactants, solvent and hydrogen charged per hour divided by the volume of the reactor employed) of about 0.25 to about 4 may be employed. A liquid hourly space velocity of about 0.5 to about 1 is preferred in the present process. Any batch type or continuous type reactors employed in the prior art are suitable for use in the present process.

After the solvent extraction operation, the resulting mixture of solvent, liquefied coal, solid coal, ash and light gases is withdrawn from the solvent extraction reactor and the liquefied coal is recovered as the product of the process. Generally, it is preferred to separate the coal liquids and solvent from the solid materials at this time by settling, filtration, centrifugation, hydroclone, extraction with light solvents such as pentane, or other similar methods well known to the prior art. Any suitable method for separating the ash and other solids from the liquid materials may be utilized in the present process. After separation of the solid materials, the coal liquids and solvent may be fractionated directly without any further treatment (i.e., hydrogenation) which has been found necessary in prior art non-catalytic coal liquefaction operation. A fraction of the liquids recovered from the extraction zone may be recycled, in a continuous type operation, for use as a part of the solvent or the whole solvent if such a fraction conforms to the essential composition of the solvent necessary to the present process.

The following examples are presented in order to contrast the process of the present invention with prior art coal liquefaction method and solvents. The examples are also presented in order to illustrate some preferred embodiments of the present process. The examples are presented for the purpose of illustration and contrast only, and are not to be considered as limitation on the generally broad scope of the present invention.

EXAMPLE I

A hydrogen-treated vacuum bottoms petroleum fraction derived from a United States crude oil, and having an initial boiling point of 840°F., was analyzed and found to contain 40 wt.% of a mixture of paraffins and naphthenes, 50 wt.% hydroaromatic compounds (hydroaromatics/saturated aliphatics weight ratio of 1.25:1) and 10 wt.% polycyclic aromatic compound. The asphaltenes (heptane-insoluble) content of this solvent was found to be 1.8 wt.%. In order to illustrate the process of the present invention, 200 grams of the above-described hydrogen-treated vacuum bottoms fraction and 200 grams of Belleville District, Randolph County Ill. stoker coal, pulverized to 100 mesh size, were placed in an 1,800 cc. rocking autoclave. The autoclave was sealed and sufficient hydrogen was intro-

duced to provide 100 atmospheres hydrogen pressure. The contents of the autoclave were heated to 750°F. and agitated at that temperature for 4 hours. The autoclave was then cooled and excess pressure was released. The mixture of liquids and solids remaining in the autoclave was removed and the solid materials were separated from the liquids by centrifuging the mixture. The solids and liquids were analyzed. The results are tabulated under Run 1 in Table I.

EXAMPLE II

A second 200 grams of 100 mesh size Illinois stoker coal was placed in the same 1,800 cc. autoclave along with 200 grams of tetrahydronaphthalene. The autoclave was sealed and sufficient hydrogen was charged to provide a hydrogen pressure of 100 atmospheres. In order to compare the process of the present invention, as embodied in Example I, with a conventional solvent extraction operation using a hydrogen donor solvent, the extraction in this run was performed in exactly the same manner as used in Example I. After 4 hours of agitation in the autoclave at 750°F., the autoclave was cooled, excess pressure was released, and the liquid and solid contents were removed and separated by centrifugation. The solids and liquids were analyzed and the results are tabulated under Run 2 in Table I.

EXAMPLE III

A third 200 gram sample of 100 mesh size Illinois stoker coal was placed in the same autoclave with 200 grams of a clarified slurry oil recovered from a catalytic cracking operation. Analysis of the slurry oil showed it to contain 7.2 wt.% hydrogen and 87.1 wt.% carbon. This solvent contained 1.3 wt.% heptane-insolubles and had an initial boiling point of 545°F. In order to compare the slurry oil as a coal extraction solvent with the solvent of Example I, which conformed to the specifications of the present process, the sample of coal in this run was extracted under the same conditions as used in Examples I and II. The autoclave was sealed and pressured to 100 atmospheres with hydrogen. The contents were then agitated at 750°F. for 4 hours. Finally, the autoclave was cooled, excess pressure was released, and the mixture of solids and liquids was removed from the autoclave, separated by centrifugation, and analyzed. The results are shown under Run 3 in Table I.

EXAMPLE IV

A fourth 200 gram sample of Illinois stoker coal was placed in the same 1,800 cc. rocking autoclave as used in the previous Examples. A 200 gram sample of raw (not hydrogen-treated) vacuum distillation bottoms was obtained from the same United States petroleum source as the hydrogen-treated vacuum bottoms used in Example I and placed in the autoclave. This solvent had an API gravity of 8.2° and contained 4.7 wt.% asphaltenes. The autoclave was sealed and sufficient hydrogen was introduced to provide 100 atmospheres hydrogen pressure. The contents of the autoclave were heated to 750°F. and agitated for 4 hours at that temperature. The autoclave was then cooled, excess pressure was released, the mixture of liquids and solids in the autoclave was removed. The liquids and solids were separated by centrifugation and analyzed. The results are tabulated under Run 4 in Table I.

EXAMPLE V

In order to further illustrate the process of the present invention a sample of hydrogen-treated vacuum bottom from a Mideastern crude oil source was obtained and analyzed. Its initial boiling point was 475°F. It contained 12 wt.% hydrogen and had an API gravity of 18.8°. This solvent contained 1.1 wt.% heptane-insolubles. A 200 gram portion of this hydrotreated vacuum bottoms sample was placed in the 1,800 cc. autoclave with 200 grams of 100 mesh size Illinois stoker coal. Sufficient hydrogen was charged to the autoclave, after it was sealed, to provide 100 atmospheres hydrogen pressure. The contents of the autoclave were then heated to 750°F. and agitated at that temperature for 4 hours. The autoclave was cooled, excess pressure was released, and the liquid-solid mixture remaining in the autoclave was removed. The liquids were separated from the solids by centrifugation and both liquids and solids were analyzed. The results are shown under Run 5 in Table I.

EXAMPLE VI

A slurry oil obtained from conventional catalytic cracking of an American petroleum, having an API number of -2°, was hydrogen-treated by processing at 700°F., 135 atmospheres hydrogen pressure, and 1 LHSV, using a conventional hydrocracking catalyst. The resulting hydrotreated slurry oil had an API number of 11.2° and contained 9.1 wt.% hydrogen. A 200 gram sample of this hydrogenated slurry oil was placed in the 1,800 cc. autoclave with 200 grams of 100 mesh size Illinois stoker coal. In order to compare the highly cyclic slurry oil with the hydroaromatic-saturate solvent mixture of the present process (Runs 1 and 5), the coal in this run was extracted in exactly the same procedure as used in Examples I and V which employed solvents conforming to the process of this invention. After the hydrogenated slurry oil and coal were placed in the autoclave, it was sealed and sufficient hydrogen was introduced to provide 100 atmospheres pressure. The contents were agitated at 750°F. for 4 hours and then cooled. Excess pressure was released and the remaining liquid-solid mixture was removed from the autoclave and separated by centrifugation. The results of analysis of the solids and liquids are shown under Run 6 in Table I.

EXAMPLE VII

A further operation using the conventional hydrogen donor solvent tetrahydronaphthalene was undertaken for the purpose of comparison with the solvents of the present invention used in Examples I and V. In this run, 200 grams of tetrahydronaphthalene and 200 grams of 100 mesh size Illinois stoker coal were placed in the 1,800 cc. autoclave and the autoclave was pressured to 100 atmospheres hydrogen pressure. As in the foregoing Examples, the mixture was agitated at 750°F. for 4 hours. After the autoclave was cooled and excess pressure was released, the liquids and solids remaining in the autoclave were removed, separated by centrifugation, and analyzed. The results of the analysis are shown under Run 7 in Table I.

Referring to Table I, by comparison of the properties of the products obtained using solvents according to the present invention (Runs 1, 5 and 8-A, described hereinafter) with a conventional hydrogen donor sol-

vent (Runs 2 and 7) and with other solvents suggested by prior art (Runs 3 and 6), it is obvious that the process of the present invention provides a superior method for solvent extraction of coal. The solvents according to the present invention provide a liquefaction product drastically lower in undesirable benzene-insoluble products and significantly lower in heptane-insoluble, asphaltene-containing products than the conventional solvents can provide under identical extraction conditions. As indicated by comparison of Run 1 (hydrogenated vacuum bottoms solvent) with Run 4 (untreated,

agitated at 750°F. for 4 hours and then cooled. Excess pressure was released and the liquid-solid mixture was removed. The solids and liquids were separated by centrifugation and analyzed. This Run was designated 8-A, 5 and the results of the analysis of the solids and liquids from this run are tabulated in Table I and Table II. In order to illustrate the lack of degradation of the unconverted coal from Run 8-A, 100 grams of the solids recovered from Run 8-A were placed in the autoclave 10 along with 100 grams more of the same 100 mesh coal and 200 grams of the same hydrogenated vacuum bottoms fraction solvent used in Run 8-A. The autoclave

raw vacuum bottom solvent), a critical property of the solvent of the present invention includes a sufficiently high content of both hydroaromatics and saturated aliphatics in the solvent as in Run 1, as opposed to condensed ring, unsaturated aromatics and unsaturated aliphatics as in Run 4. As shown by Runs 2, 6 and 7, the presence of high concentrations of hydroaromaticic components alone in a solvent, without the presence of sufficient saturated aliphatic components, provides high conversion to liquid but a very inferior, hard to process product as compared to Runs 1, 5 and 8-A (described below). In both Table I and Table II, absence of a numerical tabulation indicates data are not available.

EXAMPLE VIII

In order to demonstrate the lack of degradation of coal which is not liquefied during an extraction operation, when using the solvents of the present invention, the following operation was performed. A 200 gram sample of Illinois stoker coal was placed in the 1,800 cc. rocking autoclave. A 200 gram portion of a fraction of a hydrogenated vacuum bottoms from an American petroleum source was utilized as the solvent in this run. The vacuum bottoms for this run had been treated by processing at 760°F. and 200 atmospheres hydrogen pressure at 0.5 LHSV over a conventional catalyst. The treated product had an API gravity of 21.3°. The hydrogen-treated bottoms fraction was distilled and the 850°F. bottoms product from this distillation was used as the solvent in this run. This solvent contained 1.0 wt.% heptane-insolubles. After the coal and the solvent were placed in the autoclave it was sealed and sufficient hydrogen was charged to provide 100 atmospheres pressure. The contents of the autoclave were

35 was sealed and hydrogen was introduced sufficient to provide 100 atmospheres hydrogen pressure. The contents of the autoclave were agitated at 750°F. for 4 hours and then cooled. Excess pressure was released and the liquid and solid contents of the autoclave were removed, separated by centrifugation, and analyzed. This run was designated Run 8-B and the results are 40 shown thereunder in Table II. As a further indication of the lack of degradation of the unextracted portions of the coal, 100 grams of the solid residue resulting from Run 8-B were placed in the autoclave along with a 200 gram sample of the same hydrogenated vacuum 45 bottoms fraction solvent used in Runs 8-A and 8-B. The autoclave was sealed and sufficient hydrogen was charged to provide 100 atmospheres hydrogen pressure. The contents of the autoclave were agitated at 750°F. for 4 hours. The autoclave was then cooled and 50 excess pressure was released. The liquid-solid mixture was removed from the autoclave and separated by centrifugation. This run was designated Run 8-C. The liquids and solids were analyzed, and the results are tabulated under Run 8-C in Table II.

55 By referring to Table II, it will be apparent to those skilled in the art that processing coal according to the present invention as described in Example VIII does not result in any appreciable degradation of coal which 60 is not converted to a liquid during an extraction step. Thus, any coal which is left in a solid state after a particular extraction step using the process of the present invention may be further extracted with the solvents of the present invention to provide complete conversion 65 of the coal to desirable, distillable liquid products which are low in asphaltenes and polymerized benzene-insoluble materials.

From the foregoing description and examples, it

TABLE II

Run	8-A	8-B	8-C
<u>Properties of Liquid Product</u>			
Wt.% MAF			
Coal Dissolved	40.3	39.3	45.2
Wt.% C ₇			
Insoluble	0.9	1.25	1.07
API Gravity	21.3°	20.6°	16.2°
Wt.% Hydrogen in liquid	11.5	11.5	10.8
Unconverted Solids			
Wt.% Hydrogen in pentane insolubles (benzene insolubles)	(3.8)	4.8	4.9

is apparent that the process and solvents of the present invention provide a novel and superior method for producing liquid petroleum substitutes from coal. The coal liquids produced by the present process are superior to those produced using conventional hydrogen donor solvents and other solvents suggested by prior art. The

process of the present invention provides a method for transferring large amounts of hydrogen into the coal molecules during the solvent extraction step, a result which has not been achieved by the prior art although 5 a large variety of additives and solvents have been employed in effort to obtain such hydrogen transfer rates.

We claim as our invention:

1. A process for the production of a hydrocarbonaceous liquid which comprises solvent extracting coal with a solvent at a temperature of about 600°F. to about 850°F., a pressure of about 100 to about 350 atmospheres and a solvent/coal weight ratio of about 1:2 to about 10:1, said solvent being a hydrogenated bottoms product from vacuum distillation of crude petroleum and having an initial normal boiling point above about 400°F.

2. A process according to claim 1 wherein said solvent has an initial normal boiling point of greater than about 500°F.
